UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYING DEVICE FOR TYPEWRITING MACHINES.

Application filed January 28, 1921. Serial No. 440,618.

To all whom it may concern:

Be it known that I, WILLIAM F. HELMOND, a citizen of the United States, residing in Hartford, in the county of Hartford and 5 State of Connecticut, have invented certain new and useful Improvements in Tying Devices for Typewriting Machines, of which the following is a specification.

This invention relates to a new method of 10 tying together the movable and fixed parts of a typewriting machine for shipping purposes, and is here shown as applied, for example, to an Underwood standard typewriting machine.

15 It is an object of this invention to provide improved means for preventing movement of the carriage relative to the fixed frame of the machine both in lateral and vertical directions, and improved means for preventing relative movement of the main carriage frame and the shiftable platen-frame.

20 To prevent movement of the carriage relative to the fixed frame of the machine, there are provided sleeves adapted to fit on the rear rail and having projections adapted to engage the sides of the carriage to limit its motion to the right and left. Each sleeve is adapted to engage a bracket supporting the rear rail and to be fixed against lateral move- 25

30 ment. The projections on each sleeve are so positioned that they will engage the end walls of the carriage when the latter is centrally positioned with respect to the fixed frame of the machine. Since the distance 35 from the brackets supporting the rear rail to the end walls of the centrally-disposed carriage varies with carriages of different sizes, the projections on the sleeves must be variously disposed with respect to the sleeves. Sev-

40 eral sleeves are therefore provided, having their projections spaced at different points laterally along the surface and adapted to be used with various sized carriages. Each sleeve is provided with a set of adjacent slots 45 in its periphery, through which is adapted

to pass a band of flexible metal having a ring or round wire loop at one end. The band encircles a portion of the platen-frame and also the tabulator frame, and returns to 50 the loop or ring, through which it is drawn, and then bent back sharply. The band engages the tabulator frame, and the latter is rocked forwardly to lift the carriage rack from the escapement pinion. The band will

be held firmly in place and is easily released 55 when the machine has reached its destination. The platen-frame and the carriage are thus held at the rear against movement away from the rear rail. Similar bands are provided at the front of the machine to tie the 60 front bar of the carriage to the fixed cross-members at the front of the machine, to prevent the carriage from being displaced from the scale plate associated with the margin-gage. In this case, however, the 65 bands do not pass through sleeves, and are made somewhat wider to resist severe strain.

At the rear of the machine where the bands are drawn through slots in the sleeves, each sleeve may be provided with an addition set of slots which would obviate the use of loops or rings at the ends of the bands. After passing around a portion of the carriage frame, the bands are drawn through the second set of slots instead of 75 through the loops or rings, to prevent movement of the platen-frame relative to the main carriage frame. Bands are provided at the ends of the carriage frame, said bands passing around the end walls of the platen- 80 frame and main carriage frame.

The sleeves are made of rigid metal and can be used repeatedly.

Inasmuch as typewriters, when shipped, are supported in inverted position in the 85 shipping cases, it is obviously necessary to secure the platen-frame and the carriage firmly in position on the typewriter-frame.

Other features and advantages will hereinafter appear. 90

In the accompanying drawings,

Figure 1 is a plan view of an Underwood standard typewriting machine, showing the invention applied thereto, only the necessary co-operating elements of the machine being 95 shown.

Figure 2 is a rear view of the machine, showing the parts engaged by the flexible metal bands.

Figure 3 is a section through the side of 100 the carriage, showing the method of tying the platen-frame to the main carriage frame.

Figure 4 is an end view, partly sectioned, showing the parts engaged by the flexible bands at the front and rear of the machine, 105 the rear bands being shown in co-operation with the sleeves.

Figure 5 is an end view, showing the rear

of the machine, the flexible bands in this case not passing through the slots in the sleeves.

Figure 6 is a rear view of the method of utilizing the flexible bands as illustrated 5 in Figure 5.

Figure 7 is a view of a sleeve applied to the rear rail, and adapted for use in machines having carriages 14 or 20 inches in length.

10 Figure 8 is a view similar to Figure 7, showing a sleeve adapted for use with carriages of 12 or 18 inches in length.

Figure 9 is a view similar to Figure 7, showing a sleeve adapted for use with carriages of 10 or 16 inches in length.

15 Figure 10 is a view of one of the flexible bands provided with a ring.

Figure 11 is a detail view of a sleeve provided with a single set of slots.

20 Figure 12 is an end view of the rear of the machine, showing a sleeve provided with two sets of adjacent slots, and showing a flexible band without an end ring in co-operation therewith.

25 Figure 13 shows the size of the rear rail supporting bracket used in machines having carriages of 16, 18 and 20 inches in length, relative to the size of the bracket in a 10-inch machine shown in Figure 9.

30 A carriage 1, see Figure 4, is mounted to travel on a front rail 2 and a rear rail 3 on the fixed frame 4 of a typewriting machine.

The carriage comprises a platen-frame 10, in which is journaled a platen 11. The 35 platen-frame is connected at its ends with arms 12 fixed to a rock-shaft 13 journaled in bearings 14 forming part of the main carriage frame, and is provided at its rear with a paper-table 15. Projecting from the

40 rear of the platen-frame are brackets 16 shaped to provide portions 17, parallel to the rock-shaft 13, and upwardly and rearwardly-extending ends, in which is supported a rod 17^a to furnish a mounting for 45 the usual side-gages (not shown). The fixed portion of the machine comprises on each side thereof a rear bracket 20 in which is pivoted the lower bar 21 of a tabulator frame having an upper graduated scale-bar 22 and connecting bars 23. In this 50 frame may be mounted tabulator stops (not shown), whose upper ends co-operate with said scale-bar. At the front, the fixed frame carries a scale plate 24, with which

55 cooperate the index fingers 25 of the margin-stops 26, slidable along fixed rods 27. Referring to Figure 4, it will be noted that the rear rail 3 is fixed to bracket 20 by a comparatively thin lip 30. A sleeve 60 31 is provided with a slot 32 running lengthwise thereof said slot being of a width sufficient to allow the lip 30 to slide therein, and thus enable sleeve 31 to be slid on the rear rail. Each sleeve is of slightly greater 65 diameter than the rear rail to allow easy

movement thereon, but not sufficient to allow lateral play. At a certain portion of its length, the sleeve is provided with a semi-circumferential cut-out portion 33 of a width slightly greater than that of lip 30 and 70 symmetrically positioned on either side of the slot 32. The sleeve is slid over the rear rail with the left-hand end 34 (see Figure 11) first, the lip 30 being enclosed in slot 32. When the cut-out portion 33 reaches the lip 30, the sleeve can be rotated a quarter-turn to the position shown in Figure 4, the cut-out portion fitting over the lip 30. The slot 32 is now turned out 75 of the path of lip 30, which abuts against the sides of cut-out portion 33. The sleeve is thus held firmly in position against lateral movement.

Each sleeve is provided at its upper surface (referring to the position of the sleeve in Figure 4) with a tongue 40 cut from the surface and bent right-angularly to form a projection. It can be seen in Figure 4 that the tongues are directly in the path of the carriage, and, if a sleeve is applied to the right-hand end of the rear rail, it will prevent movement of the carriage toward the right when the left end of the machine is elevated. Since the carriage rack 42 is released from the escapement pinion 43, as will be described hereinafter, a second sleeve applied at the left-hand end of the rear rail will prevent movement of the carriage toward the left. The tongues are positioned on the sleeves in such manner that they each contact with a side of the carriage frame when the carriage is centrally positioned with respect to the main frame, and when the cut-out portion 33 is hooked over lip 30. Since the same bracket 20 is used in machines 105 having 10, 12 or 14 inch carriages, it is obvious that the tongue on each sleeve will have to be placed one inch further out for a 12-inch carriage than for a 10-inch carriage, and two inches further out for a 14-inch carriage. Figures 7, 8 and 9 show three sleeves 110 engaging the same size bracket and the relative positioning of the tongue on each sleeve. The sleeve shown in Figure 7 is to be used for a 14-inch carriage, the sleeve in Figure 8 for a 12-inch carriage, and the sleeve in Figure 9 for a 10-inch carriage. Similarly, the brackets in machines having carriages of 16, 18 or 20 inches are the same in each case, and the sleeve used on a machine having an 115 18-inch carriage must have a tongue positioned one inch further out than one used in a 16-inch carriage, and a machine having a 20-inch carriage must have a tongue positioned two inches further out. The sleeve used for a 10-inch carriage may be used for a 16-inch carriage, the sleeve for a 12-inch carriage may be used for an 18-inch carriage, and the sleeve for a 14-inch carriage may be 120 used for a 20-inch carriage.

125 Referring to Figure 4, it will be noted that the rear rail 3 is fixed to bracket 20 by a comparatively thin lip 30. A sleeve 31 is provided with a slot 32 running lengthwise thereof said slot being of a width sufficient to allow the lip 30 to slide therein, and thus enable sleeve 31 to be slid on the rear rail. Each sleeve is of slightly greater 130 diameter than the rear rail to allow easy

When the proper sleeves are applied to the rear rail, one engaging each bracket, the tongues will abut against the carriage frame at each end thereof to prevent lateral movement to the right and left. To guard against movement of the carriage in a vertical direction, each sleeve is provided with adjacent slots 41 in its periphery, adjacent the tongue and on the side toward the center of the machine, the solid strip of metal between the slots forming a strap or bridge 41^a, slightly elevated, and positioned longitudinally of the sleeve and the rail. A flat, flexible metal ribbon 51 is passed through and looped around a ring 52 substantially at its middle. The ends 50 of said ribbon are brought together to form a strap and are passed together over the portion 17 of the bracket 16, thence downward to the sleeve 31 through the slots 41 from front to rear, underneath the graduated bar 22 of the tabulator-frame, and finally through the ring 52. The ends 50 are then drawn tightly and bent abruptly back on themselves to form a bight for firmly holding the parts in place.

It is to be noted that no auxiliary or supplementary devices, as clamps, keepers, yokes, binders or bars, are used in connection with the strap, it being self-locking in operation when applied, and further, as the strap is of two-ply construction, it is easily bent into engaging position or released from the ring by bending each ply separately. It will be seen that the carriage is thus tied to the fixed frame of the machine against vertical movement, and, by drawing bar 22 forwardly, the carriage rack 42 is at the same time released from the pinion 43 of the escapement mechanism, thus preventing any injury to the latter, (see Figures 2 and 4). When the bar 22 is drawn forward, an arm 44 on the bar 21 will depress the rear end of a lever 45 fulcrumed on a pivot 46, and, by means of a wheel or roll 47 on the forward end of the lever, lift the rack 42 out of mesh with the pinion 43.

Instead of using the ring 52 to secure the ends of the tie-member 51, an additional set of slots 53 (see Figure 12) may be provided in each sleeve, and the ends of the flexible bands drawn therethrough and bent back on themselves.

The tie-member 51 may be utilized alone to tie the carriage at various points to the fixed frame of the machine. Thus at the front (see Figures 1 and 4), the band may be passed around the margin-gage scale plate and the front bar 55 of the carriage, and returned to the ring 52 where it is bent back, as previously described. A strip of cardboard 56 may be interposed between the band and the machine to prevent injury to the finish of the latter. When the tie-member is used alone, there is employed a somewhat wider strip than in the cases when

used with the sleeve, in order to provide a larger bearing surface.

Similarly, these tie-members may be utilized to bind the shifting and the main frames of the carriage together near the front of the platen, as shown in Figures 1 and 3. The bands are passed around the side plates 60 of the platen-frame and beneath the side bars 61 of the main carriage frame, and are drawn through rings 52 and bent back as usual. A strip of cardboard 62 may be inserted to prevent injury to the finish of the machine.

In larger machines, it may be advantageous to utilize several additional tie-members between the rock shaft 13 of the carriage and the bar 22 of the tabulator frame, (see Figures 5 and 6), to tie the carriage to the fixed frame of the machine and raise the carriage rack from the escapement pinion.

Variations may be resorted to within the scope of the invention, and portions of the improvements may be used without others.

Having thus described my invention, I claim:

1. In combination with a typewriting machine having a fixed frame and a movable carriage, means for tying said machine to prevent movement of the parts thereof, said means comprising sleeves mounted on the fixed frame of the machine and provided with projections adapted to abut against the carriage to prevent lateral movement of said carriage, said sleeves being removable at will, and means engaging said sleeves and carriage for preventing vertical movement of said carriage.

2. In combination with a typewriting machine having a fixed frame, a carriage and front and rear rails carried by said frame and upon which said carriage runs, means for tying said machine to prevent movement of the parts thereof, said means comprising sleeves mounted upon the rear rail and provided with projections adapted to abut against said carriage to prevent lateral movement of said carriage, said sleeves being removable at will, each of said sleeves having a set of adjacent slots, and means passing through said slots and engaging the carriage for preventing vertical movement of said carriage.

3. In combination with a typewriting machine having a fixed frame, a carriage and front and rear rails carried by said frame and upon which said carriage runs, means for tying said machine to prevent movement of the parts thereof, said means comprising sleeves mounted upon the rear rail and provided with projections adapted to abut against the carriage to prevent lateral movement of said carriage, said sleeves being removable at will, each of said sleeves having a set of adjacent slots, and a flexible band passing through said slots and engaging the

carriage for preventing vertical movement of said carriage.

4. In combination with a typewriting machine having a fixed frame, a carriage and front and rear rails carried by said frame and upon which said carriage runs, means for tying said machine to prevent movement of the parts thereof, said means comprising a sleeve mounted upon the rear rail and provided with projections adapted to abut against the carriage to prevent lateral movement of said carriage, each of said sleeves having two sets of adjacent slots in its periphery, each set of adjacent slots forming a bridge portion therebetween, and a flexible band connected to the bridge portion of one set of slots and adapted to engage a portion of said carriage and pass through the other set of slots, said flexible band being adapted to be bent back upon itself after passing through the last-named slots to tie said carriage to said frame and prevent vertical movement of said carriage.
5. In combination with a typewriting machine having a fixed frame, a carriage and front and rear rails upon which said carriage runs, said fixed frame having brackets adapted to carry said rear rail, means for tying said machine to prevent movement of the parts thereof, said means comprising sleeves mounted upon the rear rail and having cut-out portions adapted to engage said brackets to fix said sleeves against lateral movement, and having also slots enabling said sleeves to be removed at will, said sleeves having projections adapted to abut against the carriage to prevent lateral movement of said carriage, and means engaging said sleeves and said carriage to prevent vertical movement of said carriage.

6. In combination with a typewriting machine having a fixed frame, a carriage and front and rear rails upon which said carriage runs, said fixed frame having brackets adapted to carry said rear rail near each end thereof, means for tying said machine to prevent movement of the parts thereof, said means comprising sleeves mounted upon the rear rail, one near each end thereof and having cut-out portions adapted to engage said brackets to fix said sleeves against lateral movement, and having also slots enabling said sleeves to be removed at will, each of said sleeves having a projection on its periphery, said projections being so positioned as to engage the carriage at either end thereof and prevent lateral movement thereof when said carriage is centrally positioned with respect to the fixed frame, and means engaging said sleeves and said carriage to prevent vertical movement of said carriage.

7. In combination with a typewriting machine having a fixed frame, a movable carriage comprising a tabulator frame and es-

capement mechanism, including a pinion mounted on said frame and a rack on said carriage adapted to mesh with said pinion, said tabulator frame being operatively connected with said rack, means for tying said machine to prevent movement of the parts thereof, said means comprising means mounted on the fixed frame of the machine and abutting against said carriage to prevent lateral movement of said carriage, and means engaging said last-named means and the tabulator frame of said carriage to prevent vertical movement of the carriage and to rock said tabulator frame to raise said rack from said pinion.

8. In combination with a typewriting machine having a fixed frame, a movable carriage comprising a tabulator frame and escapement mechanism, including a pinion mounted on said frame and a rack on said carriage adapted to mesh with said pinion, said tabulator frame being operatively connected with said rack, means for tying said machine to prevent movement of the parts thereof, said means comprising means mounted on the fixed frame of the machine and abutting against said carriage to prevent lateral movement of said carriage, and a flexible band engaging said last-named means and the tabulator frame of said carriage to prevent vertical movement of the carriage and to rock said tabulator frame forwardly to raise said rack from said pinion.

9. A device for use in preparing for shipment a typewriting machine having a fixed frame, a carriage, and a rail on which said carriage travels, said frame having at each side a lip by which the rail is attached thereto, said device being in the form of a sleeve to be placed on an end of said rail, said sleeve having a lug to engage the adjacent end of the carriage to prevent longitudinal movement of the carriage relative to the fixed frame and having a longitudinal slot to receive the adjacent lip and a slot perpendicular to the longitudinal slot at the inner end thereof to embrace said lip so that the sleeve may be moved along the rail until the perpendicular slot is brought opposite the adjacent lip and the sleeve then turned to final position with the ends of the perpendicular slot abutting the ends of said lip to fix the longitudinal position of the sleeve with reference to the frame, and position the lug on the sleeve to engage the carriage and prevent movement thereof from a central position.

10. In combination with a typewriting machine having a fixed frame, a carriage and a rail on which said carriage travels, said frame having at each side a lip by which the rail is attached thereto, means for use in shipping to hold said carriage against endwise movement and comprising

5 sleeves to be placed on the ends of said rail, each of said sleeves having a lug to engage the adjacent end of said carriage and having a longitudinal slot to receive the adjacent lip, so that the sleeve may be moved inwardly to the proper position and then turned so as to be held by the adjacent lip against outward movement.

10 11. In combination with a typewriting machine having a fixed frame, a carriage and a rail on which said carriage travels, said frame having at each side a lip by which the rail is attached thereto, means for use in shipping to hold said carriage against 15 endwise movement and comprising sleeves to be placed on the ends of said rail, each of said sleeves having a lug to engage the adjacent end of said carriage and having a longitudinal slot to receive the adjacent lip, 20 and a slot perpendicular to the longitudinal slot, so that the sleeve may be moved inwardly until the perpendicular slot is brought opposite the adjacent lip and the sleeve then turned to final position with the 25 end of the perpendicular slot abutting against said lip.

12. In combination with a typewriting machine having a fixed frame, a carriage and a rail on which said carriage travels, 30 said frame having at each side a lip by which the rail is attached thereto, means for use in shipping to hold said carriage against endwise movement and comprising stop members for the ends of the carriage to engage the same and hold it against endwise movement from its central position, each of 35 said stop members and said rail having a bayonet-joint connection whereby the stop members may be inserted over the end of 40 the rail, moved inwardly to the proper position and there locked by being turned around said rail.

13. The combination with a typewriting machine having a fixed frame, a platen, a 45 platen-frame, a carriage in which said platen-frame is shiftable, and a rail on which said carriage travels, said fixed frame having at each side a lip by which the rail is attached thereto, of means for use in 50 shipping to hold movable parts of the machine against movement with respect to the fixed frame and comprising sleeves to be placed on the ends of said rail, each of said sleeves having a portion to engage the adjacent end of said carriage and having a longitudinal slot to receive the adjacent lip 55 and a slot perpendicular to the longitudinal

slot, so that the sleeve may be moved inwardly until the perpendicular slot is opposite the lip and the sleeve then turned to 60 final position with the end of the perpendicular slot against the lip, a loop projecting from the sleeve, and a flexible member passing through said loop and around a portion of said platen-frame to hold the 65 platen-frame and the carriage against movement away from said rail, said loop being so positioned that the tension of said flexible member will hold said sleeve against turning from said final position. 70

14. In combination with a typewriting machine having a fixed frame, a platen, a platen-frame comprising a rear paper-table, a side-gage supporting rod at the rear of the upper part of the paper-table, brackets for 75 said rod projecting from the rear of the platen-frame and having portions extending parallel to said rod, a carriage in which said platen-frame is shiftable, and a rail on which said carriage travels, means for preventing movement of said carriage and said platen-frame relative to the fixed frame comprising sleeves fitted over the ends of the rail and secured thereto in position to engage the ends of the platen-frame, and 80 flexible binding means engaging said sleeves and the portions of said brackets extending parallel to the rod to hold the platen-frame and carriage against movement away from 85 said rail. 90

15. The combination with a typewriting machine having a fixed frame comprising a cross-bar at the upper front portion thereof and a rail at the rear thereof, a carriage 95 slideable along said rail and comprising side bars and a front bar adjacent said cross-bar, and a platen-frame shiftable in said carriage, of means for preventing movement of said carriage and said platen-frame relative to said fixed frame, comprising sleeves fitted over the ends of the rail and engaging the ends of the platen-frame to prevent endwise movement of the platen-frame, and secured against outward movement on the rail, flexible binding means engaging said 100 sleeves and said platen-frame at the rear of the latter to hold the platen-frame against movement away from said rail, flexible binding means securing the platen-frame near the front thereof to the side bars 105 of the carriage, and flexible binding means securing the front bar of the carriage to said cross-bar of the fixed frame. 110

WILLIAM F. HELMOND.
